UNITED STATES PATENT OFFICE.

CLARENCE R. NELSON, OF YONKERS, NEW YORK.

HEATER FOR AUTOMOBILES AND THE LIKE.

1,108,466.

Specification of Letters Patent.

Patented Aug. 25, 1914.

Application filed June 26, 1912. Serial No. 705,981.

To all whom it may concern:

Be it known that I, CLARENCE R. NELSON, a citizen of the United States, residing at Yonkers, in the county of Westchester and 5 State of New York, have invented certain new and useful Improvements in Heaters for Automobiles and the like, of which the following is a full and clear specification.

My invention relates to heaters for automobiles, motor boats, or the like, and particularly to heaters which utilize the heat generated by the fluid-pressure engine which drives the automobile or the like.

One object of my invention is to provide 15 means for utilizing the heat generated by the engine to keep at any desired temperature a plate set in the floor of the tonneau or passenger-carrying compartment.

An additional object is to simplify the 20 construction and operation of devices of this character, and to increase their efficiency.

Referring to the drawings in which I have illustrated my invention, as applied to an automobile, Figure 1 is a plan view of my 25 device showing diagrammatically its relation to the chassis and body of an automobile; Fig. 2 is a plan view of my device with the top of the drum removed; Fig. 3 is a side elevation, and Fig. 4 is a detail of a pipe 30 union and valve.

1 represents the exhaust pipe of any fluid pressure engine which expels gases or vapor at a temperature considerably above atmospheric temperature. At 2 the exhaust pipe 35 is branched to provide two courses for the exhaust gases. The branch 3 leads to the muffler 4 in the usual manner. The branch 5 leads to the rectangular or box shaped drum 6, hereinafter referred to, and thence 40 through the outlet 7 to the muffler 4. In the union at 2 I have placed a three way valve 8, whose position determines the course of the exhaust gases through one or the other of the branches 3, 5. The valve 8 45 is operated by the right angled lever 9 which projects above the floor of the tonneau within easy reach of the occupants of the tonneau. The drum 6 is made preferably of cast iron of any suitable thickness and 50 can be of any dimensions consistent with the space available. Within the drum 6 I have placed the vertical right-angled partition 10, which extends from a point in the side of the drum between the inlet 11 and the outlet 55 7, to approximately the middle of the drum and thence, longitudinally to a point short

of the end of the drum. The partition 10 is of the same depth as the drum 6 and compels the hot gases which enter at 11 to traverse the whole space inclosed by the sides of the drum before going out at 7. It will be noted that the inlet and outlet ports are placed as close together as is practicable and in that part of the drum which is nearest to the exhaust pipe. This arrangement of the 60 inlet and outlet ports enables me to connect up the drum and exhaust pipe with short pipe lengths and thus avoid the necessity of using a longer pipe length which would cross the car body at a point where there is 65 little available space. At the same time the partition 10 insures a uniform distribution of heat over the surface of the drum.

It is obvious that the arrangement of the 70 inlet and outlet ports and the partition 10 can be varied without disturbing their functional relation if the partition is always placed between the inlet and outlet ports so as to obstruct the direct passage of the gases 75 from the inlet to the outlet.

According to the preferred construction 80 of the drum 6, it will consist of two castings, a lower casting comprising the bottom, vertical sides, and partition; and an upper or top casting which consists of a plate 85 adapted to form a panel in the floor of the tonneau and which can be corrugated or scored on its upper surface to prevent slipping.

The location of the drum in the floor of 90 the tonneau is capable of variation. The preferred position is illustrated in Fig. 1 where the top plate is seen to extend almost across the car and in convenient relation to the seat to enable the passengers to place 95 their feet on the plate. The sides of the lower casting are bent outwardly at the top (see Fig. 3) to form a flange 12. The flange 100 12 provides means for fastening the top plate to the lower casting and for supporting the drum in position.

The use of my device is not limited to 105 automobiles, but is adaptable to motor-boats or in connection with a fluid pressure engine wherever used.

What I claim is:

In an automobile heater the combination 110 of an exhaust pipe, a drum arranged with one end adjacent the exhaust pipe, said drum being provided with a partition having one portion extending longitudinally of the drum and terminating near the far end

thereof and a portion extending transversely of the drum and terminating at one side adjacent the opposite end thereof, and forming communicating passageways, short branch pipes extending from the exhaust pipe and communicating with the drum on opposite sides of the transverse portion of

the said partition and a valve for governing the flow of exhaust gases through said drum.

CLARENCE R. NELSON.
